ROCK DRILL

Ernest Craig, Falconbridge, Ontario, Canada

Application February 6, 1941, Serial No. 377,587

5 Claims. (Cl. 287—126)

This invention relates to the type of rock drill in which the cutting end or bit is detachably mounted upon the end of the drill rod and in which the securing of the bit on the drill rod shank is accomplished by a rotative movement.

The principal object of the present invention is to utilize the end thrust imparted to the drill rod by the drilling machine to effect the relative rotation of the bit to cause the bit to tighten into locking engagement with the shank.

The principal feature of the invention consists in forming the end surface of the drill rod or shank and the engaging end surface of the drill bit with corresponding spiral surfaces, which, under the impact blows of the drill, will cause the bit to rotate relative to the drill rod a part revolution in a direction opposite to the direction of rotation of the drill rod as imparted by the drill mechanism and to effect the locking engagement of the peripheral surface of the drill rod with the surrounding sleeve portion of the bit.

This invention is particularly applicable to the type of drill in which the interlocking engaging surfaces of the bit and drill rod are formed with an Archimedes spiral contour so that relative rotation of the bit and drill rod or shank causes the intimate engagement of the decreasing radius surface of one member with the increasing radius surface of the other member to effect a secure interlock and uniform contact for the transmission of impact shocks.

In the accompanying drawing Figure 1 is an elevational view of an assembled drill bit and shank.

Figure 2 is a sectional view of the improved drill bit showing the shank end of the drill rod inserted therein in elevation.

Figure 3 is an enlarged perspective detail of the end extremity of the drill illustrating my improvement.

Figure 4 is an enlarged elevational detail of the extreme end of the improved drill rod and showing it inserted within the socketed drill bit.

Figure 5 is an end view of the drill bit illustrating diagrammatically the relation between the Archimedes spiral perimeter of the shank and the spiral end surface.

Figure 6 is a perspective view of a bit embodying the present invention, the skirt or spirally surfaced sleeve portion being broken away to expose the spiral end contact surface forming the socket bottom.

It has been effectively demonstrated in practical mining operations that the type of remov-

able bit rock drill having interlocking surfaces of an Archimedes spiral formation are very practical and the interlock of the Archimedes spiral surfaces is very dependable.

It has been found desirable however to facilitate the work of the miner in placing the bit on the end of the shank. It is of course understood that in underground operations the miners are working under extreme circumstances, in that in most cases they operate entirely under the beams of small helmet lamps. Consequently it is desirable that the miner be assisted as greatly as possible in the placing of removable drill bits on the end of the drill shank with the least possible effort and where the bit and shank are formed with Archimedes spiral interlocking surfaces the practice has been to form the interfitting surfaces with a rather close range. That is to say, the bit had to be turned carefully to a fairly accurate position in relation to the shank in order to place the bit on the shank.

According to the present invention the dimensions of the Archimedes spiral of the shank are related to the dimensions of the interfitting Archimedes spiral of the bit socket so that the bit and shank will be relatively loose when they are placed together and there will be a latitude of operation or turning relationship between the two of approximately one half an inch before they definitely engage in locking contact, though this latitude is not arbitrary, but with approximately one half an inch clearance in the turning relationship of the drill and bit it becomes a comparatively simple matter for the miner to place the bit on the end of the drill shank quite easily, and then by turning the bit the bit and shank are interlocked.

It is found desirable to ensure the positive interlock of the Archimedes spiral surfaces other than through the voluntary action of the miner after he has placed the bit on the end of the shank and in order to accomplish the desired result the end face of the shank is formed with a spiral inclined surface. This is very clearly illustrated in the accompanying drawing.

The shank 1 of the drill rod 2 has its peripheral surface cut with an Archimedes spiral which is particularly illustrated in Figures 3 and 5. The end surface 3 is formed in a flat spiral formation having an incline of approximately one-sixteenth of an inch as between the highest point 4 and the lowest point 5.

The dimensions are approximately correct as shown in Figure 2 but of course are exaggerated in Figures 3, 4 and 5.

The inner peripheral wall 6 of the socket of the bit member 7 is formed with an Archimedes spiral coinciding substantially with the Archimedes spiral of the shank 1 but the internal dimensions of the socket in relation to the external dimensions of the shank are such that the bit will rotate approximately one half an inch before the surfaces engage in locking contact. This is illustrated in exaggerated dimensions in Figure 5.

The bottom face 7' of the socket is shaped to coordinate with the end face of the shank 1, it having a flat shallow spiral of corresponding dimensions.

It will be readily understood that in placing the bit on the end of the shank the socket portion is slipped over the shank end with the offset portion 8 of its surface connecting the extremities of the Archimedes spiral closely adjacent to the corresponding offset portions 9 of the shank. The bit is then quite loose on the shank but a slight turn, say of a quarter of an inch or better, will bring the surfaces of the Archimedes spiral into contact sufficient to hold the bit in place.

When the bit is then pressed against the rock which is to be drilled pressure is applied and the drill rod is rotated. The applied pressure forces the spiral end surface of the drill shank into engaging contact with the spiral bottom surface of the bit and the natural tendency is for the two engaging sloping surfaces to rotate the one on the other. This rotation of course rotates the entire bit, and the inner peripheral Archimedes spiral surface is forced into snug locking engagement with the Archimedes spiral surface of the shank, and the rotating force is sufficient to create a pressure fit.

It will of course be understood that as the bit member is formed by a forging operation and it is handled while hot the skirt or circumferential wall of the bit may be slightly deformed. The slackness of fit between the bit and the shank permits the shank to be readily inserted even though slightly deformed and the forced rotation caused by the contact of the spiral end surfaces has the effect of stretching the comparatively thin wall of the bit into snug engaging contact completely around the shank.

The manufacture of the shanks and bits in the manner described enables the operator to place the bit in position with much greater ease than if bits and shanks were made a close fit and because of the spiral end planes being engaged under vibrating pressure it is only necessary for the operator to give the bit enough twist to hold until it comes into contact with the rock face, after which it is driven into tight sealing contact so that the bits will not become dislodged from the shank.

The improvement herein described as applying a spiral surface to the end of the shank and the surface of the bit engaging therewith is herein applied to bits having locking engagement through the medium of Archimedes spiral-shaped surfaces but it will be understood that

the adaptation of an end spiral contact may be utilized in any other type of bit which requires to be turned in relation to the shank to secure it in place.

5. What I claim as my invention is:

1. A rock drill, comprising in combination, a socketed bit, a drill rod having its perimeter formed to engage in locking contact with the wall of the socket of the bit through relative

10. rotation of the rod and bit, the end of the rod having a flat spiral contact face and the bottom of the bit socket having a corresponding flat spiral contact face adapted to cause relative rotation of the bit upon the application of impact shocks to the rod to effect the locking of the perimeter.

2. A rock drill, comprising a drill rod having the perimeter of its extremity formed with an Archimedes spiral surface and having a spirally inclined end face, and a bit having the inner wall of its socket formed with an Archimedes spiral surface to engage in locking contact with the perimeter of the rod, the bottom of the socket being formed with a spiral surface to engage

20. the spiral end of the rod and adapted upon the application of impact shocks to the rod to effect the turning of the bit to bring the two Archimedes spiral surfaces into locking engagement.

3. A rock drill, comprising a drill rod and a detachable bit, the rod and bit having interlocking cam-like peripheral surfaces, the bit being formed to slip loosely over the end of the rod and adapted to be turned to interlocking

35. 35. engage said cam-like surfaces, the end of said rod having a spirally inclined surface and the bottom of the bit socket having a correspondingly shaped spirally inclined surface to that of the rod adapted to maintain a continuous end contact with the rod and to effect turning of the bit on the rod on the application of impact shocks to the rod to urge said cam-like peripheral surfaces into tight interlocking relation.

4. A rock drill, comprising in combination, a socketed bit, a drill rod having its perimeter formed to engage in locking contact with the wall of the bit socket through relative rotation of the rod and bit, and means enclosed within

50. the bit socket adapted to effect relative rotation between the rod and bit upon the application of impact shocks to urge the interlocking peripheral surfaces of the rod and bit into locking engagement.

5. In a rock drill, the combination of a drill rod having an inclined surface on its end face and an eccentric periphery, and a detachable socketed bit having an eccentric inner wall to engage in locking contact with the eccentric periphery of said rod and having an inclined

60. surface on its inner bottom wall adapted to engage the inclined end surface of the drill rod to cause relative rotation of the rod and bit upon the application of impact shocks to effect the interlocking of the eccentric peripheral surfaces.

ERNEST CRAIG.
